UNITED STATES PATENT OFFICE

JOHN A. FRENZEL, OF WAUSAU, WISCONSIN.

TRAIN-PIPE COUPLING.

No. 851,806.

Specification of Letters Patent.

Patented April 30, 1907.

Application filed August 13, 1906. Serial No. 330,371.

To all whom it may concern:

Be it known that I, JOHN A. FRENZEL, a citizen of the United States, and a resident of Wausau, in the county of Marathon and State of Wisconsin, have invented certain new and useful Improvements in Train-Pipe Couplings; and I do hereby declare that the following is a full, clear, and exact description thereof.

My invention has for its object to provide simple, economical automatic train - pipe couplings for railway air-brakes, steam-heating and signals combined; and it consists in certain peculiarities of construction and combination of parts as hereinafter fully set forth with reference to the accompanying drawings and subsequently claimed.

In the drawings: Figure 1 represents a longitudinal sectional view of a coupling embodying the features of my invention, the view being shown with parts broken away and parts in full to better illustrate the details. Fig. 2, a detail sectional view on line 2—2 of Fig. 3, showing a pair of said couplings connected, and Fig. 3, a face view of one of the coupling-members shewing the locking-hooks of its opposite member in section.

Referring by letter to the drawings, A indicates a hanger which is provided with lugs *a*, for connection to a car-body in any suitable manner. The hanger at its front end is formed with a ring *B* having vertical guides *b* for engagement with a head *C*, the head being provided with a central opening having a rear tube *D* extending therefrom, and vertically aligned channels *E*, *E'*, above and below the same. The tube is guided at its rear end in a depending ear *F* of the hanger *A*, and carries a spiral-spring *G*, which spring is under compression between the head of the pipe-coupling and the ear *F*, there being a hose-pipe coupling *H* in threaded connection with the end of said tube through which air

is supplied for the brakes, and a thrust-collar *H* projecting from the aforesaid pipe between the coupling and ear *F* in opposition to the spring. The channels or openings *E*, *E'* serve as conduits through which steam and compressed air for signal purposes is led from one car to another, each of which channels are provided with elbow-couplings *I*, *I'*, to be connected to the steam and signal pipes of the car.

The face of the head *C* is counterbored around both the central opening and chan-

nels for the reception of gaskets *c*, which are arranged to abut the gaskets of the opposite coupling and prevent leak when the union is made, it being understood that the spring *G* in each case is further compressed when the connection of the coupling is made, by reason of said couplings being forced backward when the cars are connected. Each coupling is provided with a pair of locking-hooks *J*, which are at an angle to vertical line drawn through the center of the coupling-head, and diametrically opposite each other. The said hooks, as shown, are fitted between ribs *d* projecting from the face of the head *C*, the tail-ends of the hooks being slightly turned upward, while their inner faces are provided with lugs *e*, which lugs rest in pockets of said head. The outer portion of the hooks are also formed with inner lugs *f*, which are adapted to engage flanges *K* of the opposing heads, the ends of the lugs being tapered for the purpose of lifting the same as they engage said flanges. A shoulder *g* at the outer face of each hook is arranged for contact with faces *h* of the ring, which faces, when the couplings are brought together, act to close the hooks over the flanges *K*, and also act upon the tails of said hooks to disengage the same when the couplings are disconnected.

As shown in Fig. 2, of the drawings, the rings *B* are provided with flared extensions *L* located in such a position as to engage the hook-ends and insure the same in closing, should the two coupling-members be out of alignment.

By the above described construction it will be observed that a triple pipe connection is obtained, which will insure locking of the two members, the same, by reason of the angles of the hooks from a vertical being operative without regard to the end of the car presented.

I claim:

1. A train-pipe coupling comprising a hanger provided with a forward ring having a pair of radially flared extensions at an angle intermediate of vertical and horizontal lines intersecting the axis of the ring, a rearward guide depending from the hanger, in combination with a coupling having a head provided with a plurality of openings, the head being guided in said ring, a tubular-extension from the head, supported in the rear hanger-guide, a pair of locking-dogs carried by said head, said dogs being at an angle

relatively opposite that of the flared extensions, and a spring interposed between the aforesaid head and rear hanger-guide.

2. A train-pipe coupling comprising a hanger provided with a forward ring having a pair of radially flared extensions at an angle intermediate of vertical and horizontal lines intersecting the axis of the ring, a rearward guide depending from the hanger, in combination with a coupling having a head provided with a plurality of openings, the head being guided in said ring, a tubular-extension from the head, supported in the rear hanger-guide, a pair of locking-dogs carried by said head, said dogs being at an angle

relatively opposite that of the flared extensions, front and rear projections from the aforesaid dogs arranged to be engaged by the hanger-ring, and a spring interposed between the aforesaid head and rear hanger-guide.

In testimony that I claim the foregoing I have hereunto set my hand at Milwaukee in the county of Milwaukee and State of Wisconsin in the presence of two witnesses.

JOHN A. FRENZEL.
